CLAIM

The ornamental design for a wedge insert, as shown and described.

DESCRIPTION

FIG. 1 is a front, right perspective view of a wedge insert comprising the new design;

FIG. 2 is a rear, left side perspective view of the design of FIG. 1;

FIG. 3 is a front elevational view of the design of FIG. 1;

FIG. 4 is a back elevational view of the design of FIG. 1;

FIG. 5 is a left elevational view of the design of FIG. 1;

FIG. 6 is a right elevational view of the design of FIG. 1;

FIG. 7 is a top view of the design of FIG. 1; and,

FIG. 8 is a bottom view of the design of FIG. 1.

The broken lines in the figures are directed to the environment and are for illustrative purposes only; the broken lines form no part of the claimed design.

The relatively light uneven shading represent contour, not surface decoration.
